UNITED STATES PATENT OFFICE.

JOHN J. WINGRAVE, OF NEW ORLEANS, LOUISIANA.

MOP HOLDER.

Application filed January 8, 1923, Serial No. 611,232.

To all whom it may concern:

Be it known that I, JOHN J. WINGRAVE, a citizen of the United States, residing at New Orleans, in the parish of Orleans and 5 State of Louisiana, have invented certain new and useful Improvements in Mop Holders, of which the following is a specification.

My invention relates to new and useful 10 improvements in mop holders and has for the primary object thereof, to provide such an article of manufacture that is a substantial improvement over articles of this nature, with which I am familiar.

15 The nature and advantages of the invention will be better understood when the following detailed description is read in connection with the accompanying drawings, the invention residing in the construction, 20 combination, and arrangement of parts as claimed.

In the drawings forming part of this application, like numerals of reference indicate 25 similar parts in the several views, and wherein:—

Figure 1 is an elevational view of a mop holder constructed in accordance with the present invention.

Figure 2 is an elevational view of one 30 end of my improved mop holder.

Figure 3 is a transverse sectional view taken substantially upon the line 3—3 of Figure 1, and looking downwardly in the direction of the arrows.

35 Figure 4 is a sectional view taken on the line 4—4 of Figure 1.

As clearly shown in the drawings, my device is to be associated with any desirable form of wooden handle A, the device including a neck or socket portion 5 adapted for positioning upon one end of the handle A, and being rigidly secured thereon by a cross bolt 6, the screw threaded end of which projects outwardly of the neck or 45 socket for receiving thereon a wing nut 7.

The neck or socket 5 is integrally formed upon the central portion of a cross strip or bar 8, the ends of which extend downwardly and at right angles to the said cross strip, and are designated at 9 and 10. Also formed upon this cross strip or bar 8, and upon the under surface thereof, is a web 11 secured to the strip 8 and joining the arms 9 and 10, forming a strengthening section for the member 8, the bottom edge of 50 which is serrated or toothed as at 12.

Hingedly secured as at 13 to the lower terminus of the downwardly bent end 9 of the before mentioned strip 8 is a jaw 14, which cooperates with the member 11 for retaining a mop B therebetween when the jaws are closed, as clearly shown in Figures 1 and 2. This jaw 14 is in the form of a strip of metal which is serrated or toothed as at 15 upon the upper longitudinal 55 edge thereof.

The opposite end of the jaw 14 has pivotally secured thereto as at 16, a locking lever 17, which lever constitutes the vertical portion 18, a horizontal portion 19, 70 and another vertical portion 20, this last mentioned vertical portion adapted to receive a ring or sleeve 21 thereover for retaining the jaw 14 in locked engagement. This ring or sleeve 21 is of such dimensions 75 to readily permit the same to engage over the before mentioned wing nut 7 on the cross bolt 6 when it is desired to release the locking lever 18 for subsequently swinging the jaw 14 away from the stationary jaw 11, 80 and it is to be noted that the end of this swinging jaw 14 which carries said locking lever projects outwardly from the downwardly bent end 10 of the cross strip 8, this downwardly bent end being slotted as 85 at 22 for this purpose.

In view of the above description, it will at once be apparent that when it is desired to secure a mop within my mop holder, the jaw 14 may be swung outwardly of 90 the head 11 for permitting of the insertion of the mop. By closing the swinging jaw 14 and positioning the locking lever 18 as shown in Figure 1, the mop will be firmly retained between the two jaws by 95 engaging the sleeve 21 over the vertical portion 20 of the said locking lever.

While I have herein shown and described the preferred embodiment of the present invention, it is nevertheless to be understood that minor changes may be made therein, without departing from the spirit and scope of the invention as claimed.

What I claim as new is:—

A mop holder including a cylindrical 105 socket for receiving a handle, a cross bolt adapted for removably securing the handle to the socket, said bolt normally projecting beyond the outer surface of the socket, a cross bar having the central portion secured to the lower end of the socket and provided with laterally depending end por-

2

tions having a portion thereof bifurcated, a strengthening web secured to the depending ends of the cross bar and having the free edge thereof serrated, a jaw having a serrated edge opposed to the serrated edge of the strengthening web, one end of said jaw having a pivotal connection with the end portion of one of the depending projections on said cross bar, and the other 10 end extending through the bifurcated portion of the other depending projection, a locking lever pivotally connected to the jaw beyond the depending projection on the cross bar having the free end thereof offset 15 and adapted for locking the jaw members in cooperative relation with the strengthen-

ing plate and the cross bar with the offset end positioned adjacent the socket member, and a locking ring of substantially larger size than the socket member slidably mounted thereon for receiving and holding the offset end of the locking lever, the cross bolt being adapted to prevent disengagement 20 of the locking ring from the locking lever in cooperative relation and the web cooperating with the cross bar to hold the depending end in rigid spaced relation relative to the socket and cooperates with the jaw member in holding the mop. 25

In testimony whereof I affix my signature.

JOHN J. WINGRAVE.
